ROLL MATERIAL STRIP CUTTER

John S. MacIntyre, Milwaukee, Wis.

Application May 19, 1945, Serial No. 594,777

3 Claims. (Cl. 164—84.5)

1

This invention relates to improvements in roll material strip cutters.

A general object of the invention is to provide, in connection with spool-wound roll material, a simple and convenient strip cutter adjustably mounted on an extent of the roll material and available at all times for severing desired lengths or strips of material unwound from its roll.

A further object of the invention is to provide 10 a roll material strip cutter adjustably mounted on an extent of the roll material and arranged to normally lie compactly on the surface of the roll between the side flanges of the roll spool, permitting the spool to be contained in a standard housing or container.

A further object of the invention is to provide 20 a roll material strip cutter adjustably mounted on an extent of the roll material in a manner so as to mark and locate the free end of the roll material and further permitting the free end of the roll material to be held against the surface of the roll thereby protecting the inner surface of such portion of the material against deterioration if it carries a tacky adhesive.

A further object of the invention is to provide 25 a roll material strip cutter wherein the cutter is mounted on an outer end portion of the roll material and is held in a desired position of adjustment thereon by spring tension.

A further object of the invention is to provide 30 a roll material strip cutter movably mounted on an extent of the outer end portion of the roll material itself and adapted to be housed within the confines of the spool on which the roll material is wound, which is inexpensive to manufacture, which is easily applied to roll material of all classes, which is simple to adjust and manipulate, and which is well adapted for the purposes described.

With the above and other objects in view the invention consists of the improved roll material strip cutter and its parts and combinations as set forth in the claims, and all equivalents thereof.

In the accompanying drawing in which the same reference characters indicate the same parts in all of the views:

Fig. 1 is a perspective view of a spool of roll material having the improved strip cutter applied to an outer extent of the material, the spool of material with the strip cutter on the material being shown enclosed within a housing or covering member, a wall portion of the latter being broken away;

Fig. 2 is a perspective view of a spool of roll material removed from its housing and with an extent of the roll material unwound, the end portion of the unwound extent of the material having mounted thereon the improved strip cutter;

Fig. 3 is a similar perspective view, only show-

2

ing the strip cutter moved inwardly on the unwound extent of material whereby a desired extent of the material may be severed;

Fig. 4 is a plan view of the improved roll material strip cutter on a larger scale and with a portion broken away to show structural details;

Fig. 5 is a view looking at the inner end of the strip cutter; and

Fig. 6 is a top edge view of the strip cutter.

The improved roll material strip cutter is applicable to a type of spool or core wound roll material such as adhesive tape. In the exemplification illustrated, the roll material is shown wound on a conventional metallic spool member 8 whose spaced peripheral flanges 9 provide therebetween an annular groove for the reception of the wound roll material. Besides the wound material housed on the spool between the side flanges 9 thereof, in the present adaptation, the projecting side flanges also accommodate therebetween the improved strip cutter, designated generally by the numeral 10; and which is shiftably applied to a portion of an outer extent of the roll material 11.

Said roll material 11 may be of any of the known classes of adhesive tape, but the invention finds particular utility in connection with tape carrying a pressure sensitive adhesive on its inner surface.

The improved strip cutter appliance is of a transverse dimension slightly less than the distance between the side flanges 9 of the spool, and the member 10 is likewise relatively flat so that when it is applied to an extent of the roll material 11 and said extent is in convolved position on the spool roll, the cutting appliance 10 will lie compactly between the spool flanges 9 so as to be housed thereby. Through this arrangement, with no projections beyond peripheral portions of the spool, the spool may be housed in a conventional frictionally engaged ring cover or housing 12, as in Fig. 1. When the spool is to be removed from the housing 12, it is pressed out of the open end of the same axially.

Referring now more particularly to Figs. 4, 5 and 6 of the drawing, it will appear that the improved roll material strip cutter is preferably formed of spring metal and comprises an outer or front wall portion 13 of rectangular formation having an extension portion 14 of waved formation, as best shown in Fig. 6. The rectangular front portion 13 of the member 10 has its upper edge portion folded over rearwardly, as at 15, to provide an inner edge groove 16. The opposite edge of the wall portion 13 has folded inwardly thereon a resilient plate portion 17, normally spaced slightly from inner surfaces of the portions 13 and 15. The medial part of the resilient plate 17 is offset inwardly so as to be in closely spaced relation relative to the inner surface of the portion 13 and is yieldable relative thereto.

The cutter appliance 10 is applied to a free or partially unwound extent of the adhesive roll material 11 by initially passing the lower longitudinal edge of the unwound extent of roll material into the slot between the outturned upper free end of the resilient clip 17 and the hook-like flange 15 to register the strip material with the inner faces of the portions 13 and 14, and engaging the upper longitudinal edge of the strip material under the hooked flange 15 and in the groove 16, all as is shown in Figs. 1, 2, 3 and 6. The inwardly offset medial portion of the spring plate 17 will yieldingly frictionally bear, upon slight pressure on clip 17, against the adhesive inner surface of the engaged roll material. Thus, the adhesive inner surface of the roll material causes the appliance 10 to adhere to the material in a desired position of adjustment and the appliance is thereby prevented from undesirably sliding or moving free of the outer end of the roll material.

Normally the strip cutter 10 is positioned on the outer end of the roll material 11 in the position shown in Figs. 1 and 2 with the free end of the roll material 18 projecting only slightly beyond the curved outer end flange 19 of the member 10. The inwardly bent or waved portion 19 will bear against the outer surface of the end extent of the roll material 11 to thereby press the inner surface of the same into adhesive engagement with the adjacent convolution of the roll material. Consequently the adhesive on the freed end of the roll material is held in contact with its adjacent convolution to protect the adhesive coating against deterioration.

In the use of the improved strip cutter as applied to a roll of adhesive tape, if it is desired to cut a strip of a desired length of material from the roll, the spool of material, removed from its housing or container, as in Fig. 2, has an end extent of the roll material 11 unwound to a desired length. Thereupon, the user may insert his forefinger against the inner surface of the freed end of the tape and press against the pocket formed on the inner surface of the curved extension 14, engaging the top surface of said extension with the thumb of the same hand. By engaging the side portions of the member 10 with fingers of the other hand, the tape may be pulled outwardly, breaking the adhesion, and the member 10 may be slid bodily inwardly to an adjusted position similar to that shown in Fig. 3, causing a desired extent of the roll material to be projected beyond the outer end of the adjusted member 10. Then, by firmly holding the curved extension end of the strip cutter 10 with one hand and in contact with the roll material there-adjacent and by grasping the extended portion of the roll material with the other hand, as shown in broken lines in Fig. 3, the desired length or strip of freed material may be severed from the material of the roll by tearing it across the sharp outer edge 20 of the cutter, as shown.

Successive strips of any desired lengths may be severed by repeating the operation described. After a strip or a series of strips have been severed from the roll material, it will be observed that the cutter appliance 10 will be mounted on an outer end portion of the roll material in about the condition of Fig. 2. This is very convenient for the storing of the spool, as it is merely necessary to wind the outer extent of the roll material onto the spool and the free end of the material may be pressed into adhesion onto the adjacent convolution to hold it in position. As

was previously mentioned, the inwardly bent portion 19 of the extension will bear against the outer end of the roll material to maintain it in engagement with the inner convolution. The spool as thus arranged may then be redisposed within its protective housing or ring enclosure.

Transparent adhesive tape, such as "Scotch" tape, when in roll form, is quite difficult to use because the end of the outermost convolution 10 may not be readily detected ordinarily. The present invention finds additional utility in connection with such types of tape because, being applied to the end of the roll material, it definitely acts as a marker or locating device therefor, besides serving as an adjustable means incorporated on the roll material for permitting the easy severance of strips of desired lengths.

The improved roll material strip cutter is inexpensive to manufacture, is easily applied to roll adhesive tape material and remains associated therewith so as to be available for use at all times, is compact, is easy to manipulate and is well adapted for the purposes described.

What is claimed as the invention is:

- 25 1. In combination with a standard spool formed with a pair of spaced side discs and elongated material wound on the spool between said discs, of a flat appliance shiftably mounted only on an outer end portion of said material and lying compactly thereon between the faces of the spool discs and inwardly of the peripheral portions of said discs, said appliance in its operative position being movable free of the spool with the outer end portion of the material carrying the appliance.
- 30 2. The combination with a roll of flat adhesive tape material, of an appliance shiftably embracing an outer end portion of the outermost convolution of the roll material, said appliance having an outer wall and an inner resilient plate portion spaced therefrom, opposite margins of the outer wall portion being formed with turned U-shaped flanges to engage and embrace opposite margins of the flat adhesive tape material extended between the outer wall and the inner plate portion of the appliance, the appliance also having a transverse edge portion to cut an outer extent of the roll material freed from the roll and pulled outwardly thereagainst.
- 35 3. In combination with a core having elongated flat adhesive tape wound thereon, of a flat appliance shiftably mounted only on an outer end portion of said tape material and lying compactly thereon, said appliance in its operative position being movable free of the normal perimeter of the wound material with the outer end portion of the tape material releasably adhering to a portion of the appliance and carrying the latter.
